[57] CLAIM

The ornamental design for an animal habitat, as shown and described.

DESCRIPTION

FIG. 1 is an perspective view of an animal habitat showing our new design;

FIG. 2 is an enlarged scale top plan view thereof;

FIG. 3 is an enlarged scale front elevational view thereof;

FIG. 4 is an enlarged scale rear elevational view thereof;

FIG. 5 is an enlarged scale left elevational view thereof;

FIG. 6 is an enlarged scale right elevational view thereof; and,

FIG. 7 is an enlarged scale bottom plan view thereof. The connecting pipe segments in all figures are broken away to show indeterminate length.

FIG. 1

FIG. 3

FIG 4

FIG. 5

FIG. 6

FIG. 7
